Patented Oct. 15, 1929

UNITED STATES PATENT OFFICE

PAUL H. TODD, OF KALAMAZOO, MICHIGAN

SOAP

No Drawing.

Application filed May 25, 1927. Serial No. 194,234.

This invention relates to germicidal soap. The object of this invention is to provide an improvement in germicidal soaps, particularly in mercuric germicidal soaps. It is a particular object to increase the germicidal quality and modify the harshness of such soap.

Heretofore, an effective germicidal soap has been prepared by incorporating about 10 two per cent of a mercuric salt, for example mercuric iodide, in a good ordinary toilet soap base. Such a soap, though strongly 15 germicidal, is harsh in its effect upon the skin owing to the corrosive action of the combined mercury.

I have found that by using a mercuric salt in conjunction with cresol in soap, it is possible to obtain a soap with a high degree of efficiency as a germicide, but with a considerably milder action upon the skin, this latter 20 quality being evidently due to the greater effectiveness of mercuric salts when used in conjunction with cresol, making it possible to use a considerably smaller percentage of 25 the mercuric salt and still obtain a soap with a high germicidal efficiency. There is what might be called a synergistic relation between the germicidal actions of soluble mercuric salts and cresol.

30 I have found, for example, that a good ordinary soap base made from cocoanut and olive oils, in the proportion of two parts by weight of olive oil to four of cocoanut oil, properly saponified with caustic soda, and 35 impregnated with one per cent of mercuric chloride and ten per cent of cresol, kills *Staphylococcus aureus* and *Bacillus coli* within five minutes at 20° C. in an eight per cent solution, that is, when the organisms 40 are immersed for five minutes in a solution of eight grams of the soap in ninety-two grams of water.

In preparing my soap, I have as an example taken by weight 400 parts of cochin 45 cocoanut oil and 200 parts of olive oil and saponified the mixed oils with 106 parts of caustic soda dissolved in 214 parts of distilled water, stirring the alkali into the oils and crutching until saponification was well 50 under way. I then heat the mixture until

the saponification is completed. I then crutch 10.3 parts of mercuric iodide in a solution prepared by dissolving 8 parts of potassium iodide in 15 parts of water. I then crutch the same after heating to a boiling point into the soap together with 103 parts cresol, U. S. P. After thorough crutching the hot soap is poured into a small soap frame where it is cooled and cut up ready for use.

The improved soap can be prepared by taking a good quality of toilet soap like the well known Ivory and milling or crutching my special ingredients into it.

Having thus described my invention what I claim as new and desire to secure by Letters Patent is:

A soap composition containing cresol 1% to 15% and mercuric iodide $\frac{1}{4}\%$ to 3%.

In witness whereof I have hereunto set my hand.

PAUL H. TODD.
